UNITED STATES PATENT OFFICE.

CLAIBORN CLARK, OF LOS ANGELES, CALIFORNIA.

RAILROAD-CROSSING.

1,340,750.

Specification of Letters Patent. Patented May 18, 1920.

Application filed April 19, 1919. Serial No. 291,275.

To all whom it may concern:

Be it known that I, CLAIBORN CLARK, a citizen of the United States, residing at Los Angeles, in the county of Los Angeles, State 5 of California, have invented new and useful Improvements in Railroad-Crossings, of which the following is a specification.

The present invention relates to railroad crossings.

10 The invention embodies improvements that are particularly applicable to shockless crossings which comprise turn-tables that are operated by the wheels of the car that is approaching the crossing.

15 A further object of the invention is to provide a mechanism that is not dependent upon any particular size of wheel flange for its proper operation and which will not be damaged by too great a movement caused 20 by the exceptionally large wheel flange. The invention provides a crossing that will always be operated accurately by either a small or a large wheel flange. Further objects of the invention and the details of the 25 construction of a preferred form of the invention will be clearly understood from the following detailed description, in which reference is had to the accompanying drawings, in which—

30 Figure 1 is a plan view of a single track intersection with the cover plates removed in order to show the mechanism; Fig. 2 is an enlarged detail section taken as indicated by line 2—2 of Fig. 1; Fig. 3 is an 35 enlarged detail section taken as indicated by line 3—3 of Fig. 1; Fig. 4 is a detail section taken as indicated by line 4—4 of Fig. 3; Fig. 5 is an enlarged detail section taken as indicated by line 5—5 of Fig. 4; Fig. 6 is an enlarged detail section taken as indicated by line 6—6 of Fig. 5; Fig. 7 is a view 40 similar to Fig. 6, showing the position of the parts when the mechanism has been operated; Fig. 8 is an enlarged section taken as indicated by line 8—8 of Fig. 1; Fig. 9 is a 45 plan view of a portion of the crossing with the turn-tables 10 rotated 90° from the position shown in Fig. 1; and Fig. 10 shows a block that may be substituted for the turn-table.

50 In the drawings numeral 10 designates turn-tables which are mounted in base plates 11. There is a base plate, and a turn-table, at each rail intersection; and in the crossing about to be described there are four rail 55 intersections. The invention, as shown and described is applied to a single track right

angle crossing but it will be understood however, that the invention is not limited to this particular form of crossings but may be applied to crossings in which the rail 60 intersections are at any angle. The turn-tables 10, which are best shown in Fig. 2, are circular disks mounted in seats 12 in the base plates 11. In the top of each turn-table there is a groove 13 which extends diametrically across the turn-table. Across the top of the base plates 11 there are grooves 14 and 14^a. Rail sections 15 and 16 which are bolted to flanges 17 that project from base plates 11 have grooves 18 in 70 them. The grooves 13, 14, 14^a and 18 are so shaped as to allow wheel flanges to extend into them and they are sufficiently deep to receive the flanges and not allow them to run on the bottom of the grooves. The 75 rail sections 15 and 16 are fastened to base plates 11 in such a manner as to cause the grooves 14 and 18 and grooves 14^a and 18^a to come in alinement. The turn-tables 10 are rotatable in the seats 12 thereby making 80 it possible to turn the tables in such a manner as to cause grooves 13 in blocks 10 to come in alinement with the grooves 14 or 14^a. The turn-tables 10 are all inter-connected as hereinafter described, so as to cause 85 them to operate together and to keep grooves 13 parallel. The turn-tables 10, as shown in Fig. 1 are in a position in which grooves 13 are in alinement with groove 14 which would allow a car to pass over the crossing 90 either from A or from B, and the car wheels will pass over the crossing without jarring or bumping, as the wheels have a smooth surface over which to run. In order to allow a car to pass over the crossing either 95 from C or from D the blocks 10 must be rotated in such a manner as to cause the grooves 13 to come in alinement with the grooves 14^a. This rotation of the turn-tables 100 is caused by the flanges of the wheels, which are about to pass over the crossing, striking levers which operate the mechanism about to be described.

Operating rods 19 which are pivotally connected at 19^a to lever arms 20 extend 105 into slots 21 in turn-tables 10 and are pivotally connected to the turn-tables at 19^b by means of pins 22. The lever arms 20 which are pivotally connected at 20^a to push rods 23 are pivotally mounted at 20^b on brackets 110 24. The brackets 24 are mounted at 25 on base plates 11. The push rods 23 pass

through openings 23^a in rail sections 16 and are pivotally connected at 27 to lever arms 26. The lever arms 26 are pivotally mounted on brackets 28 which extend 5 from rail sections 16; and pivotally connected to lever arms 26 at 26^a are push rods 29 which are pivotally connected at 30 to lever arms 31. The lever arms 31 extend from sleeves 32 which are keyed 10 to shafts 33 by means of pins 34. The shafts 33 extend transversely between the rail sections 15 and have blocks 35 keyed to them at each end by means of pins 36. Bolted to the inner sides of rail sections 15 15 are plates 37 which have pins 38 on them. The pins 38 extend inwardly and engage slotted sockets 39 in blocks 35. The pins 38 are of the shape shown in Figs. 6 and 7. They have round surfaces 40 and flattened 20 surfaces 41. The sockets 39 in blocks 35 are shaped as shown in Figs. 6 and 7, there being a circular portion 42 in which the pins 38 fit, and a circular curved slotted portion 43 in which the pins 38 may slide when 25 block 35 is in the relative position shown in Fig. 7. The blocks 35 have short lever arms 44 which are pivotally connected at 45 to connecting rods 46 which are pivotally connected at 47 to operating levers 48. The 30 operating levers 48, pivotally mounted at 49 to rail members 15, extend into the grooves 18 of the rail members, the flanges 18^a being cut away, as shown in Fig. 3. The operating levers 48 in sections C and D in Fig. 1 35 are in the up-position as shown in Fig. 3, while the operating arms in sections A and B are in the down position, the mechanism having been operated so as to cause the grooves 13 and 14 to be in alignment. 40 Wheel flanges engaging operating levers 48 at section C or D will cause downward movement of said levers and through connecting rods 45, will cause levers 44 and castings 35 to move in the direction indicated by the arrows in Figs. 3 and 6, thereby causing 45 a rotation of shaft 33. This rotation of shaft 33 will cause movement of lever arms 31 in the direction shown by the arrow in Fig. 3. The movement will then be transmitted to turn-tables 10 through the system of push rods and levers, hereinbefore described, the rods and levers moving in the directions indicated by the arrows in Fig. 1 50 to the position shown in Fig. 9. The turn-tables 10 will be moved through an angle of 90° thereby causing grooves 13 to come into alignment with grooves 14^a which will permit a car to pass over the crossing either from section C or from section D. The 55 downward movement of levers 45 will cause shaft 33 to rotate on pins 38 just enough to cause the rotation of turn-tables the desired amount. When shaft 33 has been rotated this amount casting 35 will be in the position shown in Fig. 7. Further movement of

levers 48 will then cause blocks 35, to be slid over pins 38. The blocks 35 and the shaft 33 will then swing around the pivoted connection 30 instead of rotating. The slots 43 of sockets 39 are curved around the center 70 of connection 30. In order to prevent over travel of the turn-tables due to sudden operation or for any other reason, brackets 56 are mounted over lever arms 19. The surfaces 57 and 58 form stops for the arms 75 19. The brackets 56 also hold the lever arms 19 against the surfaces 11^a of the base plates 11 and thereby hold the turn-tables in the base plates.

Springs 50 are arranged under the operating arms 48 so as to tend at all times to keep the arms up. Due to the fact that there is a spring under each arm the springs equalize or balance each other and therefore do not tend to cause operation of the mechanism. The springs are merely to assist the mechanism in returning from a depressed position and to keep the mechanism tight. The mechanism, which is all below the level of the tracks, is covered by means of cover 80 plates 51 which rest on lugs 52 on rail sections 15 and 16, the cover plates having been removed in Fig. 1 in order to clearly show the mechanism. The lever arms 20 are interconnected by means of connecting rods 85 53, 54 and 55, as shown in Fig. 1. This connection of lever arms 20 causes operation of all of the turn-tables 10 by the operation from any side. The interconnection and the general arrangement of the mechanism 90 is such as to cause the operating levers 48 at A and B to be raised when the levers at C and D are depressed and also to cause the levers at C and D to be raised when the levers at A and B are depressed. The push 95 rods 29 are provided with turn-buckles 29 thereby providing a means by which adjustment may be made in the mechanism.

The construction and mounting of the turn-tables is very simple and permits easy 100 and rapid replacement or repairs and if for any reason it should become necessary or desirable to make the crossing similar to the ordinary form of crossing this could be done by disconnecting and removing the shockless turn-table and fastening in the seat a block having two intersecting grooves as shown in Fig. 10.

Having described a preferred form of my 105 invention, I claim:

1. A track intersection of the character described, embodying an intersection mechanism, an operating means, a connecting mechanism between the intersection mechanism and the operating means and positive 110 mechanical means in said connecting mechanism which allows overtravel of the operating mechanism without causing overtravel of the intersection mechanism.

2. A track intersection of the character 115

described, embodying a mechanical intersection mechanism, a mechanical operating means for said intersection mechanism, a wholly mechanical connecting mechanism between the intersection mechanism and the operating means and positive mechanical means in said connecting mechanism to allow the operating means to overtravel without causing the intersection mechanism to 10 overtravel.

3. A track intersection of the character described, embodying a mechanical intersection mechanism, a mechanical operating means for said intersection mechanism, a mechanical 15 connecting mechanism between the intersection mechanism and the operating means and mechanical means in said connecting mechanism to allow the operating means to overtravel without causing the intersection 20 mechanism to overtravel, said means embodying a pivot pin engaging a socket block so as to cause predetermined relative rotary motion of said pin and block.

4. A track intersection of the character 25 described, embodying a mechanical intersection mechanism, a mechanical operating means for said intersection mechanism, a mechanical connecting mechanism between the intersection mechanism and the operating 30 means and mechanical means in said connecting mechanism to allow the operating means to overtravel without causing the intersection mechanism to overtravel, said means embodying a relatively moving pivot 35 pin and socket block.

5. A track intersection of the character described, embodying a mechanical intersection mechanism, a mechanical operating means for said intersection mechanism, a 40 mechanical connecting mechanism between the intersection mechanism and the operating means and mechanical means in said connecting mechanism to allow the operating means to overtravel without causing the intersection mechanism to overtravel, said means embodying a relatively moving pivot 45 pin and a socket block, said socket block being movable relatively to the pin both pivotally and slidably.

50 6. A track intersection of the character described, embodying a mechanical intersection mechanism, a mechanical operating means therefor, and a mechanical connecting mechanism between the intersection mechanism and the operating means, said last mentioned mechanism embodying a 55 member adapted by its rotation to transmit motion through to the intersection mechanism, a pivot pin for said member, a socket 60 in said member engaging said pivot pin, and said pivot pin and socket being of such configuration as to allow sliding motion of said member with relation to the pivot pin after a predetermined amount of rotation.

65 7. A track intersection of the character

described, embodying a mechanical intersection mechanism, a mechanical operating means therefor, and a mechanical connecting mechanism between the intersection mechanism and the operating means, said 70 last mentioned mechanism embodying a socket block having a lever arm connected and movable therewith, said lever arm being pivotally connected at its end to a connecting rod which transmits motion to the intersection mechanism, a pivot pin engaging said socket block, the socket in said block embodying a circular portion adapted to fit around the pin and provide a bearing whereon the socket block and its connected lever 75 may swing upon the pin as a pivot, and said pin being flattened and said socket having a slotted portion in a curvature centered upon the center of connection of said connection rod with said lever arm, so that 80 when said socket block has rotated through a predetermined angle to a position where said slotted socket portion is in line with the flattened faces of the pin then the socket block may slide upon the pin and the socket 85 block and its lever swing about said connecting rod connection as a center.

8. A track intersection of the character described, embodying a mechanical intersection mechanism, stop means to positively 95 limit the movement of the intersection mechanism at both ends of its movement, a mechanical operating means for said intersection mechanism, a wholly mechanical connecting mechanism between the intersection mechanism and the operating means and positive mechanical means in said connecting mechanism to allow the operating means to overtravel without causing the intersection mechanism to overtravel.

9. A track intersection of the character described, embodying a mechanical intersection mechanism, stop means to positively limit the movement of the intersection mechanism at both ends of its movement, 100 a mechanical operating means therefor, and a mechanical connecting mechanism between the intersection mechanism and the operating means, said last mentioned mechanism embodying a socket block having a 110

lever arm connected to and movable therewith, said lever arm being pivotally connected at its end to a connecting rod which transmits motion to the intersection mechanism, a pivot pin engaging said socket block, the socket in said block embodying a circular portion adapted to fit around the pin and provide a bearing whereon the socket block and its connected lever may swing upon the pin as a pivot, and said pin being flattened and said socket having a slotted portion in a curvature centered upon the center of connection of said connection rod with said lever arm, so that when said socket block has rotated through a predetermined angle 120 125 130

to a position where said slotted socket block may slide upon the pin and the socket block and its lever swing about said connecting rod connection as a center.

5 10. In a track intersection mechanism, a socket block having a circular portion adapted to fit around a flattened pin and provide a bearing whereon the socket block may swing upon the pin as a pivot, and a 10 slotted portion adapted to receive the pin when the block is rotated to a pre-determined position, so that the socket block may slide on the pin.

11. In combination in an intersecting 15 mechanism, a stationary flattened pin, and a movable socket block adapted to coöperate

with the pin, the socket block having a circular portion adapted to fit around the pin and provide a bearing whereon the socket block may swing as a pivot, and a slotted 20 portion adapted to receive the pin when the block is rotated to a pre-determined position, so that the socket block may slide on the pin.

In witness that I claim the foregoing I 25 have hereunto subscribed my name this 14th day of April, 1919.

CLAIORN CLARK

Witness:

VIRGINIA BERINGER.
